UNITED STATES PATENT OFFICE.

HENRY R. CASSEL, OF NEW YORK, N. Y.

APPARATUS FOR RECOVERING PRECIOUS METALS FROM REFRAC- TORY ORES.

SPECIFICATION forming part of Letters Patent No. 694,350, dated March 4, 1902.

Application filed June 12, 1901. Serial No. 64,199. (No model.)

To all whom it may concern:

Be it known that I, HENRY R. CASSEL, a citizen of the United States, and a resident of New York city, county and State of New York, have 5 invented certain new and useful Improvements in Apparatus for Recovering Precious Metals from Refractory Ores, of which the following is a specification.

This invention relates to an improved apparatus for carrying into practice a process for recovering precious metals from refractory ores—such as tellurides, sulfids, or other compounds containing them—and for which an application for a patent has been filed by 15 me on even date herewith under Serial No. 64,198.

In the accompanying drawing Figure 1 is a vertical transverse section of my improved apparatus on line 1 1, Fig. 2. Fig. 2 is a side 20 elevation, partly broken away, of the same; Fig. 3, a transverse section of two adjoining lining-plates *c*; Fig. 4, a detail cross-section through the shaft *i* on line 4 4, Fig. 5; and Fig. 5, a section on line 5 5, Fig. 4.

25 The letter *a* represents a vat of suitable dimensions and provided with openings, valves, or taps *b* for the discharge of the pulp.

The inner face of the vat *a* is lined with carbon plates or blocks *c*, that form an electrode. The inner or exposed side of each plate *c* is notched or recessed at both ends, as at *c'*, so that when the plates are placed side by side parallel grooves are formed at the joints for the reception of metallic conducting-strips *d*. These strips extend over the joints and are secured to the plates by means of bolts *e* and nuts *e'*, they being thus readily accessible for the purpose of replacement and repair. The strips *d* are covered 35 within the grooves by layers of cement *f*, which protect them against the electrolytic action. They receive the current from a dynamo or other source of electric energy through wire *g* and convey it directly to the carbon lining. Between the carbon lining and the side of the vat *a* I interpose a backing of cement *h*, which serves to properly connect the parts, prevent leakage, and to increase the 45 stability of the electrode.

50 Across the vat *a* extends an insulated metal shaft *i*, driven by pulley *i'*. To this shaft are affixed the radially-projecting stirring-blades,

which are composed of a metal arm or core *j* and of carbon covering-plates *j'*, that constitute the second electrode. The carbon plates 55 *j'* project beyond the edges of the arms *j*, and the surrounding groove thus formed is filled in with cement, as at *k*, so that the arms *j* are completely covered up. The arms *j* are connected to the shaft *i* in such a manner by 60 bolts or otherwise that the electric current passes freely from contact *i*² through the shaft and arms to the carbons.

In operation the ore converted into pulp by the admixture of water containing sufficient 65 salt to render it conductive is charged into the vat while the stirrers are revolved. Simultaneously the current is turned on to decompose the chlorid of sodium until the refractory elements in the pulp are sufficiently oxidized and the gold is set free and dissolved, 70 the current precipitating the dissolved gold in the form of a black powder. A suitable solvent, such as cyanid of potassium, is now added to redissolve the gold, which is then 75 separated from the pulp and precipitated for final recovery.

The current is preferably reversed from time to time or an alternating current is used, which assists in preventing the precipitation 80 of the gold on the electrodes, causes it to remain in the pulp, and keeps the electrodes clean.

What I claim is—

1. In an apparatus for electrolytically recovering precious metals from ores, the combination of a vessel with a lining composed of grooved carbon plates, and of metal conducting-strips contained within the grooves of said plates, substantially as specified. 85

2. In an apparatus for electrolytically recovering precious metals from ores, the combination of a vessel with a lining composed of grooved carbon plates, a backing of cement between the vessel and lining, metal conducting-strips within the grooves of said lining, and a cement covering above the metal strips, substantially as specified. 90

3. In an apparatus for electrolytically recovering precious metals from ores, the combination of a vessel with a rotatory insulated shaft, metal arms projecting radially therefrom, carbon plates projecting beyond the arms, and a cement filling between the plates 100

and around the arms, substantially as specified.

4. In an apparatus for electrolytically recovering precious metals from ores, the combination of a vessel with a carbon lining and metal strips in contact therewith to form one electrode, and rotatable stirrers composed of metal arms and a carbon covering that form the second electrode, substantially as specified.

5. In an apparatus for electrolytically recovering precious metals from ores, the combination of a vessel with a grooved carbon

lining, metal conducting strips within the grooves of said lining, a cement covering 15 above the strips, an insulated shaft, metal arms projecting radially therefrom, and a carbon covering affixed to said arms, substantially as specified.

Signed by me at New York city, county and 20 State of New York, this 10th day of June, 1901.

HENRY R. CASSEL.
